UNITED STATES PATENT OFFICE.

SIDNEY WACHTEL AND SAM REISS, OF BOSTON, MASSACHUSETTS.

PIN-TICKET.

1,193,319.

Specification of Letters Patent.

Patented Aug. 1, 1916.

Application filed July 23, 1915. Serial No. 41,602.

To all whom it may concern:

Be it known that we, SIDNEY WACHTEL and SAM REISS, citizens of the United States, and residents of Boston, county of Suffolk, 5 State of Massachusetts, have invented an Improvement in Pin-Tickets, of which the following description, in connection with the accompanying drawing, is a specification, like characters on the drawing representing like parts.

This invention relates to improvements in marking devices such as pin tickets and one of the objects thereof is to provide a device of this character in which the attaching 15 members engage the material at a greater number of points than is usual in marking devices of this character now upon the market thereby more securely fastening the marking device to the merchandise and also 20 preventing the same from moving laterally while attached thereto.

Another object of the invention is to provide a device of this character which can be more easily attached to the merchandise than 25 the usual forms of pin tickets and without the danger of the pins spreading apart as they are being inserted into the merchandise.

Another object of the invention is to provide means adapted to wholly conceal the 30 ends of the pins in such a manner that they cannot snag either the fabric to which the pin ticket is attached or other fabrics with which the same may be associated, or prick the hands of any one handling the merchandise.

Other objects of the invention will more 35 fully appear from the following description and drawings and will be pointed out in the annexed claims.

In the drawings; Figure 1 is a plan view 40 of one of the preferred forms of ticket embodying our invention, Fig. 2 is a perspective view of the reverse side of the ticket illustrated in Fig. 1, Fig. 3 is a longitudinal 45 sectional view on lines 3—3 Fig. 1, showing the ticket applied to a piece of fabric, Fig. 50 4 is an illustration of a different embodiment of our invention in which the recess for receiving the end of the pin is in the form of a depression in the ticket instead of 55 an aperture therethrough as illustrated in Fig. 3, Fig. 5 is a longitudinal sectional view on lines 5—5 Fig. 4, Fig. 6 is an underside plan view of another embodiment of our invention, and Fig. 7 is a sectional view on lines 7—7 Fig. 6.

Pin tickets which have heretofore been constructed comprise usually a staple affixed to a suitable card, the legs of the staple projecting at right angles thereto. In affixing 60 such tickets to merchandise such as cloth or garments the legs of the staple are forced through the garment and then spread apart until they lie in contact therewith. Unless unusual care is taken in such instances the 65 points of the staple project sufficiently to engage adjacent layers of fabric or other fabrics brought into contact therewith and frequently snag and damage the same. The staples of pin tickets of this character penetrate the fabric only at two points and are 70 more or less easily displaced.

One of the objects of the invention as above stated is to provide a pin ticket with a staple, the legs of which may be through 75 the fabric in two or more places so that the staple of each ticket will be provided with four points of engagement with the fabric and another feature of the invention comprises the provision of means for inclosing 80 and protecting the ends of the staple after the ticket is affixed to the cloth. In the embodiment of the invention illustrated in Fig. 1 this is accomplished by providing the usual cardboard body 1 with a staple consisting 85 of parallel legs 2, joined by the intermediate portion 3. The staple is preferably inserted in the card at a considerable distance from the edge thereof as illustrated in the drawing. The staple after having been passed 90 through the cardboard from the face thereof toward the reverse side desirably may be provided with offsets 4 to clench the staple firmly against the card, the legs of the staple being thereafter bent at right angles 95 thereto in such a manner as to lie parallel to the edges of the card.

The tips 5 of the staple desirably are slightly curved upwardly or in the direction of the face of the card as illustrated in Fig. 100 2. This construction accomplishes a two-fold purpose. First, it facilitates the application of the pin ticket to the merchandise and second insures the complete protection of the point when the pin ticket is affixed 105 to the merchandise.

In applying a ticket of this character to the merchandise the cardboard is taken between the fingers of the operator and the pins of the staples thrust downwardly 110 through the fabric, then the cardboard is depressed toward the plane of the surface

- of the fabric causing the points of the pin to rise through the fabric at a distance from the point of penetration, corresponding approximately to the distance from the transverse portion 3 of the staple to the end of the card. The points having thus emerged from the fabric are then bent back upon themselves until the curved tips 5 enter recesses 6 provided in the card. It will thus be obvious that when the pin ticket is thus affixed to the merchandise there will be four points of engagement with the cloth approximately at the points 7, 8, 9 and 10 illustrated in the drawings.
- 15 The recesses 6 may comprise openings passing entirely through the card as illustrated in Figs. 1, 2, and 3 or they may be formed as intaglio depressions 12 in the card as illustrated in Figs. 4 and 5. In such case 20 the portion upon the reverse face of the card which is in relief presents walls or fillets 13 against which the shanks 2 of the staple lie closely.

It will thus be obvious that in this construction when the pin ticket is applied to the merchandise in the manner aforesaid the shanks 2 of the staple will be prevented from spreading as the staple is thrust into the fabric, thus insuring the parallelism of the 25 pins during the penetration of the fabric and preventing the stretching or crinkling of the cloth between the pins. When the pins have been thus inserted they are bent around the edge of the card in the manner aforesaid until the tips 5 engage or penetrate the bottom of the depression 12. In 30 this form of device the tips of the pins are positively prevented from engaging either the fabric to which the pin tickets are attached or other fabrics which may be brought into contact therewith.

A further embodiment of our invention is illustrated in Fig. 6 which comprises a combination of the forms illustrated in Figs. 1, 45 2, 3, and 4, 5. In this form the aperture extends through the ticket but is preferably in the form of a slot 15 having walls 16 which are depressed through the reverse side of the ticket in such a manner as to form projections of the character shown in Fig. 5 so that by lying alongside of the shanks of the staple they will prevent the staple from spreading in the manner above described.

It will be understood that the disclosure 50 of the invention herein is illustrative merely

and not restrictive and that the invention may be embodied in other forms within the meaning and scope of the following claims.

Having thus described our invention what we claim as new and desire to secure by Letters Patent is:

1. A pin ticket comprising a card, a staple affixed thereto at a distance from the edge thereof, the legs of the staple extending in parallelism beyond the edge of the card, recesses intermediate of the points of attachment of the staple to the card and the end of the card adapted to receive the bent back tips of the staple. 65

2. A pin ticket comprising a card, a staple affixed thereto at a distance from the edge thereof, the legs of the staple extending in parallelism beyond the edge of the card, and having upwardly curved tips, recesses intermediate of the points of attachment of the 75 staple to the card and the end of the card adapted to receive the curved tips of the staple.

3. A pin ticket comprising a card, a staple affixed thereto at a distance from the edge 80 thereof, the legs of the staple extending parallel to the reverse face of the card and to a distance beyond the edge thereof, recesses formed by depressing portions of the card adjacent to the staples so that the reverse face of the card will lie adjacent the shanks of the staple whereby the displacement of the legs of the staple when thrust into the merchandise is prevented and the recess thus formed provides protection for 85 the bent-over end of the staple. 90

4. A pin ticket comprising a card, a staple affixed thereto at a distance from the edge thereof the legs of the staple extending parallel to the reverse face of the card and 95 to a distance beyond the edge thereof, recesses in the form of narrow slots having walls extending from the reverse face of the card and adapted to engage the legs of the staples and maintain them in parallelism 100 while the ticket is being applied to the merchandise, said slots forming apertures to receive the ends of the staple when the staple is bent back upon itself from the edge of 105 the card.

In testimony whereof, we have signed our names to this specification.

SIDNEY WACHTEL.
SAM REISS.
